Primary Examiner — Kevin K. Rudzinski

Assistant Examiner — Richard Kearney

(57) **CLAIM**

The ornamental design for a stopper for zippers, as shown and described.

DESCRIPTION

FIG. 1 is a front elevational view of a stopper for zippers showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a third perspective view thereof;

FIG. 10 is a fourth perspective view showing the stopper for zippers in a state of use;

FIG. 11 is a fifth perspective view showing the stopper for zippers in a state of use;

FIG. 12 is a sixth perspective view showing the stopper for zippers in a state of use; and,

FIG. 13 is a seventh, perspective view showing the stopper for zippers in a state of use.

The broken lines in FIGS. 10-13 depict environment and are for illustrative purposes only and form no part of the claimed design.

1 Claim, 13 Drawing Sheets
